(57) **CLAIM**

I claim the ornamental design for the decorative wine bottle, substantially as shown and described.

DESCRIPTION

FIG. 1 is a top, front perspective view of a decorative wine bottle;

FIG. 2 is a left side elevational view of the decorative wine bottle, where the right side elevational view, the front elevational view, and the back elevational view are identical images thereof;

FIG. 3 is a top plan view of the decorative wine bottle; and, FIG. 4 is a bottom plan view of the decorative wine bottle. The broken lines shown in the drawings are for the purpose of illustrating portions of the article that form no part of the claimed design.
